UNITED STATES PATENT OFFICE.

JAMES P. FREEMAN, OF CHICAGO, ILLINOIS.

TELEPHONE-EXCHANGE SYSTEM.

SPECIFICATION forming part of Letters Patent No. 308,248, dated November 18, 1884.

Application filed July 30, 1884. (No model.)

To all whom it may concern:

Be it known that I, JAMES P. FREEMAN, a citizen of the United States, residing at Chicago, in the county of Cook and State of Illinois, have invented certain new and useful Improvements in Telephone-Exchange Systems, of which the following is a specification, reference being had therein to the accompanying drawings.

10 My invention relates to telephone-exchange systems; and it consists in a novel construction and arrangement of the parts, which will be more fully hereinafter described, and pointed out in the claims.

15 The object of my invention is to provide means for establishing a quick communication between any number of telephonic subscribers, and, by means of suitable colors representing like conducting-bars arranged in benches or steps, confusion is avoided in intercommunication by the operator, whether there be a large or small number of said steps or benches, by merely connecting bars of like colors. I attain these objects by the device illustrated in the accompanying drawings, forming a part of this specification, and wherein like letters refer to similar parts, and in which—

Figure 1 is a perspective view of my improved exchange system. Fig. 2 is a transverse vertical section thereof. Fig. 3 is a detail view of one of the plugs or stops, showing its connection to the rear or line plates. Fig. 4 is a detail view of one of the conducting-bars of metal. Fig. 5 is a detail view showing the manner of putting the conducting and non-conducting bars together, and the plug-contact rod resting against the conducting-bar. Fig. 6 is a detail view showing 40 the manner of applying the line-plates to the rear of the benches or steps. Fig. 7 is a detail view showing a modification in the construction of the conducting and non-conducting bars.

45 A A represent the steps or benches of my improved exchange system, which may be of any number and proportion.

B is the annunciator, which is secured to the benches A A in any suitable manner.

50 C C are the drops of the annunciator, with

the usual figures on their faces, and operated in the well-known way by coil and armature-lever.

D represents the plugs or stops, which are cylindrical in form and have secured to their ends a contact-rod, E, which is connected to a line-plate, F, at which the line-wire terminates by means of a spring, G, the other ends of said stops or plugs D being suitably headed, with numbers or letters on their faces corresponding to those on the annunciator-drops C.

I I are the ground-plates, against which the contact-rods on plug D rest when not in use, and which are all connected to ground.

K represents the local battery to the operator's telephone. 1, 3, and 5 are bars of conducting material, preferably metal, which are insulated from each other by means of non-conducting bars 2, 4, and 6, of suitable insulating material, such as wood or rubber. These conducting and non-conducting bars are arranged alternately and parallel, and form the steps or benches of my improved exchange system, the plugs D and their contact-rods E having free motion in grooves or slots O O, cut therein, as shown in Figs. 4 and 5.

M M are the ground-wires running from the ground-plates I I.

S is a switch of the ordinary form connecting the metal conducting-bars 1, 3, and 5 with the operator's telephone.

g g g are the wires connecting the conducting-bars 1, 3, and 5 to the exchange operator's switch S.

S' S' are the switches connecting the listeners or loop in telephone to the bars 1, 3, and 5 by means of wires a a a, running from said switches to the conducting-bars.

To construct my improved exchange system, proceed as follows: Provide an annunciator, B, of the ordinary form, with the numbered drops C, actuated by the magnetic attraction and repulsion of an armature-lever on a coil, as is usual. Take the required number of conducting-bars 1, 3, and 5, and arrange them parallel and against each other, and clamp or fasten them in any suitable manner, so that the holes O O can all be bored, and slots o cut in the same by a single operation. The non-

conducting-bars 2, 4, and 6 are arranged in like manner and the same operation performed upon them, with the exception that the holes O O are made of larger diameter, for a purpose which will be presently described. These bars of conducting and non-conducting material, of suitable proportions, are then arranged against each other alternately and parallel and secured together by means of insulated screws or bolts, as is well known in the art. By the combination of these bars 1, 3, and 5, and 2, 4, and 6, alternately, as described, the benches A A are formed, and to the uppermost of which the annunciator B is rigidly secured. A plug or stop, D, is then constructed in a cylindrical form of insulating material and of suitable diameter to engage with the holes O O in the bars of conducting and non-conducting material, forming the benches. These plugs D are provided with suitable heads, upon the faces of which are placed the numbers or letters corresponding to those on the annunciator-drops. To the other ends of these plugs a contact-rod, E, is secured and extends up through the short slots o to aid the operator in seeing how far to draw said plug out to put it in contact with the required strip or bar. This slot O O, with its smaller slot o in the alternate conducting and non-conducting bars when they are secured together in benches, forms a continuous slot extending the entire width of the said benches or steps.

To the contact-rod E a spring, G, is secured to allow the plug D to take its normal position when not in use. Immediately against the back portion of the benches, and partially covering the holes O O and slots o of the bars 1, 3, 5 and 2, 4, 6, is fastened a metal ground-plate, I. This ground-plate I is in turn covered by a strip of any insulating material having mounted thereon the line-terminal plates F. To these line-terminal plates F are secured the other ends of the springs G on the contact-rods E, said springs passing through and having free movement in apertures i of the ground-plates I.

When the rods E of plugs D are drawn away from their ground-plates I and brought in contact with one of the conducting-bars, and consequently the ground-connection thereby broken, it is put to ground through the operator's instrument, being electrically connected therewith by said bars and their connections, so that he will be enabled to communicate with the subscriber.

When the plugs D are not in use, their contact-rods E rest against the ground-plates II, which are all connected by wires M M to one line running to ground. The line-terminal plates F of the several benches are all connected up together and run by a single line from each series to the corresponding annunciator-coil, and from thence to line.

The conducting-bars 1, 3, and 5 in the benches are connected either by wires b b b, as shown, or by metal strips fastened to bars oc-

cupying the same position, so as to form a continuous bar of the whole series. To render these conducting-bars more easily distinguishable and to facilitate the operation 70 of my exchange system, it will be found desirable to have each one of the conducting-bars painted a different color. For instance, if 1, 3, and 5 of the first bench are colored or painted red, white, and black, the bars in the 75 remaining benches, occupying the same position and being electrically connected, will respectively have the same color, so that one plug, having been placed in contact with a colored bar of one bench of a series of benches, 80 the operator need only place the requisite plug of any of the other benches on a like-colored bar, when the entire series of bars, by means of their electrical connections, will form one entire conducting-bar. 85

By having the holes or slots in the non-conducting bars of larger diameter than those of the conducting-bars a contact-bearing-surface is allowed the point of rod E on the plugs D when turned slightly to one side to form the 90 connection.

In Fig. 7, the series of bars of conducting and non-conducting material are shown as being flared at their ends, said flared ends being adapted to receive the contact-rod on 95 the end of the plug or stop when it is turned from one side to the other, as desired, and hold said contact-rod, and thus dispense with the use of the grooved and slotted form, as shown in the drawings. 100

The operation of my exchange is as follows: For instance, if subscriber No. 1 should wish to communicate with No. 11, he first rings the signal-bell in his office, and the current coming in over the line-wire 1 will cause drop 105 No. 1 of the annunciator to fall, showing the exchange operator that No. 1 desires to be connected with some other subscriber. The operator at once pulls plug No. 1 out a sufficient distance, and in doing which breaking its 110 ground-contact to allow the pin to engage with some bar not in use. He then turns his switch to the same bar through his connecting-wire with the same, asks No. 1 which subscriber he wishes, and in answer requests 115 No. 11. The operator now pulls plug No. 11 out, breaking its ground-contact, until its contact-rod E rests against the corresponding bar in the second bench, (see Fig. 7,) and rings up No. 11, who, upon answering his 120 call, is told to go ahead. As soon as the subscribers have ceased their communication, a short ring or signal will let the exchange operator know that they are through, when he then turns plugs 1 and 11 far enough to 125 release the contact-rods E from their contact with the bars upon which they rest, and through the resiliency of the springs G on their ends are drawn back against the ground-plates I, and thus grounded and ready for another call. 130

I do not confine myself to the exact con-

struction shown. For instance, the spring G may be dispensed with, and a weight and cord attached in its place, the object of both being to bring the stop back to its normal position 5 automatically after being released from the communicating bars.

It will also be seen that the annunciator can be replaced by galvanometer needles, when the 10 action will be the same. These and other changes in construction can be made without materially departing from the nature and principle of my invention.

Having thus described my invention, what I 15 claim as new, and desire to secure by Letters Patent, is—

1. In a telephone-exchange system, the combination of an annunciator, alternate conducting and non-conducting parallel bars arranged in benches or steps, and stops or plugs 20 for making electrical connections, substantially as described.

2. In a telephone-exchange system, the combination, with an annunciator, of a series of 25 conducting and non-conducting bars arranged parallel and in benches or steps, plugs or stops with contact-rods, the ground-plates, and electrical connections, substantially as described.

3. In a telephone-exchange system, the combination, with the annunciator, of a series of 30 insulated and conducting bars arranged parallel and in benches or steps, insulated plugs having contact-rods at their ends, springs con-

nected to said contact-rods, the line-terminals to which the other ends of said springs are attached, the ground-plates, and electrical connections, substantially as described. 35

4. In a telephonic-exchange system, the combination, with the annunciator, of a stepped switch-board, composed of a series of slotted or grooved conducting and non-conducting 40 parallel bars, secured together and electrically connected to form one circuit, the insulated plug, with its contact-rod bearing in the grooved switch-board, the spring on one end of said contact-rod, the ground-plates, the line 45 terminal-plates to which the free end of contact-rod springs is secured, and their electrical connections, substantially as and for the purposes described.

5. The combination, in an exchange system, 50 of annunciator B, switch boards or benches A, composed of alternate bars of parallel conducting and non-conducting materials 1 3 5 and 2 4 6, slots or grooves O O, and small slot o, plug D, contact-rod E, spring G, line-terminal plates F, ground-plates I, operator's switch S, and the electrical connections, substantially as described. 55

In testimony whereof I affix my signature in presence of two witnesses.

JAMES P. FREEMAN.
